UNITED STATES PATENT OFFICE.

JOSEPH W. SCHLOSS, OF NEW YORK, N. Y., ASSIGNOR TO JOSEPH W. SCHLOSS CO., A CORPORATION OF NEW YORK.

COLLAR-SUPPORTER.

1,200,884.

Specification of Letters Patent.

Patented Oct. 10, 1916.

Application filed March 16, 1915. Serial No. 14,673.

To all whom it may concern:

Be it known that I, JOSEPH W. SCHLOSS, a citizen of the United States, residing at the city of New York, in the borough of Manhattan and State of New York, have invented certain new and useful Improvements in Collar-Supporters, of which the following is a full, clear, and exact description.

10 This invention relates to collar supporters such as are commonly used for stiffening ladies' collars made from lace or other flimsy material, which do not possess sufficient inherent stiffness to maintain themselves about the neck without wrinkling. 15 The common type of a supporter used for this purpose comprises a filamentary structure having an attaching eyelet at each end.

The object of my invention is to provide 20 a collar supporter of this general character, which is of a simple construction, and which may be cheaply and economically manufactured in large quantities. Accordingly, the supporter is formed from a single length or 25 piece of wire by bending the end portions over the intermediate part to provide three parallel strands of substantially equal length, which are twisted together to form the filamentary structure. The attaching 30 eyelets are simultaneously formed from the loops which connect the end portions of the piece of wire with the intermediate part. Preferably, uncovered wire is used in making the supporter and a coating of enamel 35 is applied to the supporter to cover the exposed ends of the wire and to prevent them from catching the skin or hair of the wearer. This coating may also be applied to the remainder of the supporter to prevent the 40 wire from rusting when the garment to which it is attached is laundered.

Another object of the invention is to improve the shape of the attaching eyelet so 45 that the supporter may be firmly and securely fastened to the collar. To do this, I provide each eyelet with two seats for the stitches which attach it to the collar so that the supporter will be held by the stitches against both longitudinal and lateral 50 placement without danger of the supporter slipping.

In the accompanying drawings, Figure 1 shows my improved form of collar supporter, Fig. 2 shows the same article in 55 partially completed state; and Fig. 3 is a

detail showing the enamel coating over the exposed ends of the wire.

Broadly speaking, the collar supporter consists of a filament structure 1 having attaching eyelets 2 and 3 at the ends of the supporter, which may be made of varying lengths, depending upon the height of the collar with which it is to be used. The supporter is constructed from a single length or piece of small gage, flexible wire, 60 by bending the end portions of the piece over the intermediate part to provide three parallel strands 4, 5 and 6, which are connected at opposite ends by loops 7 and 8. The strands are of substantially equal length 65 and the loops extend out beyond the same so that when the wire is twisted the filamentary structure, which has been designated 70 1, is produced, while the eyelets 2 and 3, are simultaneously formed by the closing 75 of the loops in the twisting operation. By forming the supporter from a plurality of strands twisted together in the manner described, the filamentary structure produced 80 possesses the necessary rigidity and strength 85 to act as a stiffener for a collar and yet permit a relatively fine gage, flexible wire to be used which may be readily bent and twisted either by hand or machine, at a relatively low cost.

In forming the supporter, the ends 9 of 90 the piece of wire are exposed and frequently are sufficiently sharp to engage the skin or hair of the person wearing the collar supporter, if they are not protected, such engagement resulting in a scratching of the skin, or otherwise causing annoyance or discomfort to the wearer. To protect the exposed ends I preferably use an uncovered wire in forming the supporter and after it 95 has been completed coat the same with a protective covering 10 of enamel or like material. As the strands are of substantially equal length the exposed ends 9 occur at the point of junction between the eyelets and the filamentary structure so that when the enamel coating is applied to the supporter the exposed ends will be entirely covered by the excess of enamel 12 which collects at this point. The surface of the collar supporter is therefore perfectly smooth and there is no danger or likelihood of its surface causing any discomfort to the person wearing the supporter.

While I find it preferable to coat the en- 110

tire collar supporter with enamel, yet if the coating is applied over the exposed ends to act as a protective covering for the same, it will suffice, although this method of applying the coating is objectionable where an uncovered wire is used, since the supporter may rust if the garment to which it is applied is laundered without removing it.

The eyelets 2 and 3 are preferably shaped 10 to provide seats for the stitches which secure it to the collar, and this is preferably accomplished by making the eyelets of a triangular shape instead of circular, as is the usual construction. One apex 10 of each of 15 the triangular shaped eyelets occurs at the junction between it and the filamentary structure and the side 11 opposite this apex is substantially perpendicular to the longitudinal axis of the supporter. In this manner, two seats are provided in each eyelet 20 at the ends of the side 11. To apply the supporter, attaching stitches 12 are taken which pass through each eyelet and around the portions of the same forming two seats, 25 two or three stitches around each seat being sufficient, since they are prevented from slipping by the sharp bend in the eyelets at each of these points. The seats of both eyelets are, moreover, disposed so that they oc-

cur at the corners of a rectangle, and as 30 long as the stitches hold any longitudinal and lateral displacement of the supporter will be prevented.

I claim:

1. A collar supporter comprising a filamentary structure formed from a single length of wire having its end portions bent parallel to its intermediate part and twisted therewith, a protective covering over the exposed ends of said wire, and eyelets at the 35 ends of said structure consisting of loops formed in bending said wire.

2. A collar supporter comprising a filamentary structure formed from a single length of wire having its end portions bent 40 parallel to its intermediate part and twisted therewith, said end portion and intermediate part being of substantially equal lengths, a protective covering over the exposed ends 45 of said wire, and eyelets at the ends of said structure consisting of loops formed in bending said wire.

In witness whereof, I subscribe my signature, in the presence of two witnesses.

JOSEPH W. SCHLOSS.
